CLAIM

(51) **LOC (10) Cl.** **12-15**

The ornamental design for a tread portion of an automobile tire, as shown and described.

(52) **U.S. Cl.**

DESCRIPTION

USPC **D12/604**; D12/579

FIG. 1 is a perspective view of a tread portion of an automobile tire showing my design;

(58) **Field of Classification Search**

FIG. 2 is a front view thereof;

USPC D12/568-604, 900

FIG. 3 is a top view thereof;

CPC B60C 1/0016; B60C 11/0306; B60C

11/0302; B60C 3/06; B60C 9/17

See application file for complete search history.

FIG. 4 is a right side view thereof;

(56) **References Cited**

FIG. 5 is a fragmentary enlarged view showing the details of

U.S. PATENT DOCUMENTS

the tread portion thereof;

D713,328 S * 9/2014 Umstot D12/579

FIG. 6 is a section view taken along line 6-6 in FIG. 5; and,

D728,456 S * 5/2015 Allison D12/579

FIG. 7 is a section view taken along line 7-7 in FIG. 5.

D728,457 S * 5/2015 Reim D12/580

The broken lines are used to show portions of the tire that are

D730,272 S * 5/2015 Fleckner D12/580

not being claimed, and thus form no part of the claimed

design.
